UNITED STATES PATENT OFFICE.

JAMES M. ELDER, OF INDIANAPOLIS, INDIANA.

IMPROVEMENT IN CULTIVATORS.

Specification forming part of Letters Patent No. 222,391, dated December 9, 1879; application filed August 30, 1879.

To all whom it may concern:

Be it known that I, JAMES M. ELDER, of Indianapolis, in the county of Marion and State of Indiana, have invented a new and useful Improvement in Cultivators, of which the following is a specification, reference being had to the accompanying drawings.

The object of my invention is to provide a system of newly constructed and arranged devices for keeping the shovels of the plow in the ground; also, to facilitate the lifting of the shovels when it is desired to raise them; also, to relieve the weight of the tongue from the horse's neck.

My invention consists in the new construction and arrangement of devices; also, in the new combination of elements which are deemed essential in my newly-organized apparatus, as will be first fully described in the specification, and then set forth in the claims.

In the accompanying drawings, in which like letters of reference in the different figures indicate like parts, Figure 1 represents a perspective view of one side of a cultivator embodying my improved apparatus. Fig. 2 is a front elevation of the same. Fig. 3 is a side, and Fig. 4 is a top, view of the coupling device. Figs. 5 and 6 represent a top and side elevation of the forked bracket, and Fig. 7 is a sectional view of the cup that supports the lower end of the spring.

A represents the wheel of the plow-sulky, which is mounted on the axle B. The axle B forms part of, or is secured to, the arch-bar C, in the usual manner.

T is part of the tongue-brace, which is provided with a hook, U, to hang the plow-beams on, and is secured to the arch C also, in the usual manner. The plow-shovels X X are also attached to the plow-beams W W, and provided with the plow-handle V, in the usual manner.

To the arch-beam C is attached a downward-projecting arm, E, the lower end of which is connected with the downward-projecting part C' of the arch-beam by a bolt or shaft, Y, on which is mounted the pipe or cylinder D, which is free to rotate on the bolt Y. To the pipe D is pivoted the forked coupling device F by the pin a.

To the rear end of the coupling F the plow-beams W W are secured, as shown in Fig. 1. On one side of the coupling F is a lug or boss, G, having a serrated face, s, in which fits the serrated face of the extension part G'. The outer end of the part G' is provided with a vertical groove, m', and an eyebolt, n, as shown in Figs. 3 and 4.

The rod H is securely clamped in the groove m' by the eyebolt n, as shown in Fig. 1. The upper end of the rod H is hinged or pivoted at d to the rod I, and the rod I is provided with a cup-shaped piece, J, Fig. 7, which is securely riveted to the rod in the position shown in Fig. 1. The lower end of the spring K rests in the part l of the cup, and the rod I passes through the hole i. The rod I extends upward through the spring K, above the arch-beam C, as shown.

The bracket O is constructed similar to that shown in Fig. 5—that is, with the arms g' g projecting forward from one side, in which is pivoted the universal joint, composed of the parts L L', with joint-arms pivoted at m. The lower part, L', is also made cup-shaped, to receive the upper end of the spring K and hold it in position. The bracket O is securely fastened to the arch-beam C, or to the arch-beam and auxiliary arm E, by clamps R r, or by any other ordinary means, such as bolts, &c., as shown in Figs. 1 and 2.

It is obvious that the bar E may be dispensed with, and the bolt Y form a stud projecting from the arch-beam C' to receive the pipe D; also, the bracket O might be secured to the arch-beam, and support the spring device independent of the bar E.

The operation of my improved device is as follows, to wit: When the plows are in the position shown in Fig. 1 the spring E tends to force the plows into the ground, the degree of force being regulated by the position in which the serrated lugs G G' occupy on the coupling F. Thus, if the lugs G be set back in the holes t, Fig. 3, the pressure exerted on the shovels will be greater than if the lugs were in the position shown.

If it is desired to raise the shovels, as in moving the cultivator from place to place, the handle V is raised, at the same time tipping

the upper end of the rod H forward in front of the axle, thus forming an angle with the rod I. The spring K then presses down on the rod H, helping to raise the shovels, thus rendering them easier to be lifted and hung on the hook U. The toggle-joint, composed of the parts L L', with joint m, permits the adjustments of the bracket O to any desired point on the arch-beam relative to the position of the plow-beams on the axle. Thus the device can be attached to any ordinary cultivator, rake, or other implements.

I am aware that prior to the date of my invention cultivators had been provided with springs which acted with a lifting action upon the beams, and with increasing force as the beams ascended; and I am also aware that springs had been so applied as to serve the double purpose of holding the beams down when in action, and of lifting or assisting to lift them when they were raised above an operative position, and therefore I do not claim said features, broadly; but I am not aware that any one has hitherto constructed and ap-

plied a spring in the manner shown in the accompanying drawings, and

What I claim, therefore, is—

1. The adjustable bracket O, combined with the universal joint L L', spring K, cup J, rod I, and coupling G, as and for the purpose specified.

2. In combination with the arched axle of a cultivator, the bracket O, with arms g g, the universal joint L L', the spring K, the cup J, the rod I, the rod H, the serrated lugs G G', the coupling F, and plow-beams W W, as and for the purpose specified.

3. In combination with the coupling F of a shovel-beam, the jointed rod H I, spring K, universal joint L L', and bracket O, as and for the purpose specified.

In testimony whereof I have signed my name to this specification in the presence of two subscribing witnesses.

JAMES M. ELDER.
